O. H. Taylor

United States Patent Office.

O. H. TAYLOR, OF BROOKLYN, NEW YORK.

Letters Patent No. 96,505, dated November 2, 1869; antedated October 23, 1869.

IMPROVEMENT IN BIT-STOCKS.

The Schedule referred to in these Letters Patent and making part of the same.

To all whom it may concern:

Be it known that I, O. H. TAYLOR, of the city of Brooklyn, county of Kings, and State of New York, have invented a new and useful Improvement in Bit-Stocks; and I do hereby declare that the following is a full and exact description thereof, reference being had to the accompanying drawings, and to the letters of reference marked thereon.

The nature of my invention consists in making the socket of a bit-stock with a projection on the side (when said socket is made solid or non-adjustable as to size) opposite the screw, so that the said projection will set under the shoulder of the shank, or that part of the bit that enters the socket, when arranged within the same, the object being to prevent the bit from slipping out, when the screw is set against the side opposite the aforesaid projection or ridge.

I also make an opening on the side of the socket that has the projection on, so that the bit may be readily seen, for the purpose of adjusting to the proper entering-distance.

The object of my invention is to produce a cheap bit-stock, that will hold a bit in a secure manner, without adjusting.

To enable others skilled in the art to make and use my invention, I will proceed to describe its construction and operation.

Figure 1, in the accompanying drawing, is a side elevation of my improvement, showing the socket, by dotted lines, with a bit-shank inserted.

Figure 2 is a front view of the same.

Figure 3 is a back view.

Letters of like name and kind, refer to like parts in all the figures.

I construct my bit-stock in any of the known forms, except that portion D D, (shown in all the figures,) that holds the bit, the socket A of which I make larger than is usual, at its lower end, and form a pro-

jection on one of its sides, at the lower portion, shown at C, fig. 1, said projection being formed for the purpose of setting under the shoulder of the bit-shank, (when said shank is properly inserted in the socket,) to prevent the same from slipping out, when the screw, or its equivalent, is forced against its side, opposite the aforesaid projection.

The socket A is made wider the way the screw runs than the opposite or right-angle way, the difference being that of the projection C, so that the bit-shank shoulder, or its largest part, may be inserted beyond the projection, until the side of the shank next to it comes to a fair bearing beyond it, there being an opening formed at G, so that the bit may be readily seen, for the purpose of adjustment, as aforesaid.

The socket is made sufficiently large to receive any ordinary bit-shank shoulder beyond the projection C. By this mode, they may be firmly secured within the same, by the aid of a thumb-screw, J, or its equivalent, without any fitting.

I am aware that bit-stock sockets, or pieces forming them, have been provided with similar projections, and for the same purpose that I have made them, that of preventing the bit from slipping out; but I am not aware that a solid, unadjustable socket was ever provided with a projecting ridge, as herein described, and for the purpose set forth.

Having thus fully described my invention, What I claim as new, and desire to secure by Letters Patent, is—

The socket D D, with opening G and lip C, when all the parts are constructed as described, and for the purposes specified.

O. H. TAYLOR.
